UNITED STATES PATENT OFFICE.

ASA E. LINENDOLL, OF NORWALK, OHIO.

VEHICLE HEATER.

Application filed December 18, 1922. Serial No. 607,589.

My invention relates to vehicle heaters which utilize the exhaust gas from the motor for the heating medium, and has for its object to provide a heater of that type which will be efficient and leak proof, especially proof against any possible entrance of the heating medium into the heated compartment.

One of the objects of my invention is the provision of a device adapted to be placed in the floor of a vehicle, and which, though capable of being disassembled from above, the joints between the heater coils in the casing and the exhaust or escape pipes shall be outside the heater casing and below the floor of the vehicle.

Other features of the invention will appear as the description proceeds, and will be specifically pointed out in the appended claims.

Referring to the accompanying drawings forming a part of this specification:

Figure 1 is a plan view of a heater embodying my invention, a portion of the cover plate being broken away at one end;

Figure 2 is a transverse section of the heater taken on the line 2—2 of Fig. 1;

Figure 3 is a side view, partly in elevation and a part in longitudinal section;

Figure 4 is a horizontal section of parts as they would appear on the line 4—4 of Fig. 3, and

Figure 5 is a view of the washer or packing for my leak-proof joint.

The heater consists of a casing having vertical walls 11 at the ends and sides and a bottom 13. Within the casing is held the heating tube 10 which is integral, but may be of any form desired, it being only essential

that the ends of the coils shall be located in proper position over the openings 15 in the bottom of the casing to make possible the connection with the exhaust or escape pipes as will be later explained.

The heater is adapted to be seated in the floor of the vehicle with its upper surface substantially flush with the floor as indicated by 12 in Figs. 2 and 3. The upper edges of the casing body have a projecting flange 14 upon which the cover plate 20 may rest, a downwardly projecting flange 21 bearing against the inner surface of the casing wall and serving to hold the said plate in proper position.

In the bottom of the casing is a circular

opening 16 which is closed at will by a detachable plate 17 of corresponding shape and which is provided with a peripheral flange resting on the edge of the opening. A bridge bar 18 shown only in section in Fig. 3 but in elevation in Fig. 2, serves to connect the lower plate of the casing with the cover plate, so that the latter will be readily removable. There are three of these bars 18 all of which are alike, and all serving a similar function, as will be later more fully explained.

Immediately above the plate 17 is an apertured sleeve 19 which is made integral with the coils 10 and bears down upon the plate 17 to cover the opening 16 tightly when pressure is exerted downwardly upon the tubes 10. This is accomplished by providing the center of the middle bar 18 with a threaded opening to receive the lower threaded end 75 of a screw bolt 22 having a head seated in the cover 20, passing down through the sleeve 19, through an opening in the plate 17, and by rotation from above, serving to hold the cover 20 rigidly down upon the flange 14, 80 and also to press the ends of the bar 18 tightly up against the casing bottom, but not touching the plate 17, for obvious reasons.

Other bolts 23 at either side of the central bolt 22, screw into the central aperture of a 85 bar 18 beneath the casing and bear downward upon a slightly extended flange integral with the tube 10, thus serving not only to hold the tube 10 and its sleeve 19 down upon the plate 17 but also bearing upward on the casing bottom. At the ends of the tubes 10 are flanges 24 which serve to make convenient manual removal of the coils, as my heater can be dismantled from the interior of the vehicle—above the car 95 floor.

In the form of heating coils which is used to embody the invention now disclosed, the tube 10 is made up of two lengths as shown in Figs. 1 and 2, which lengths unite at their 100 ends to provide a common downwardly extending tube 26 for suitable connection with the exhaust and escape pipes. This tube 26 is integral with a reduced extension 25 by which a shoulder 27 is formed for a purpose 105 to be later stated, the reduced pipe closely fitting the opening 15 though movable through it. The lower edge of the pipe 25 extends below the plane of the casing bottom 13, and connection is made from it to 110

the exhaust or escape pipes 32 by providing the latter with a reduced end or sleeve 28 of suitable size to enter the coil extension, the sleeve having an outstanding enlarged 5 flange 31 forming a shoulder upon which the pipe end 25 rests when the connection is made. An asbestos washer 30 is provided for fitting between the extensions 25 and flanges 31, and making the joint quite leak- 10 proof.

For seating the coils desirably upon the casing floor, a dished annular metal washer 29 is snugly fitted about the pipe 25 just beneath the shoulder 27 so that the down- 15 ward pressure of the tube 10 is exerted upon the casing wall 13 yieldingly, for the ring 29 is within the casing. The screws 23 will serve to take up a reasonable amount of resistance in said ring. The pipes 32 are reduced somewhat beneath the flange 31, the latter resting upon and about the edge of an opening in a rectangular metal piece 33. This cap piece 33 is angular in longitudinal section, as seen in Fig. 3, thus providing 20 flattened edges or flanges 34 which are riveted at 35 to the casing bottom 13, as shown in Figs. 3 and 4. The screw 23 passes loosely through the said flange 34, and the bar 18 is spaced above the flange, as shown in 25 Fig. 2, bearing against the casing at its ends. This cap piece 33 is therefore open at each end, as shown at the left end of Fig. 3, so that if gases should by any possibility leak 30 from the joint at 30, they would be wholly 35 outside the casing, and would escape below the car floor at such open ends of part 33.

This insurability of gases being confined within the tubes 10, while the parts are assembled, arises from the fact that all tube 40 parts above the casing bottom are integral thus making leaking therefrom absolutely impossible. The only place from which gases can possibly leak is at the joint between the heating tube and exhaust pipe 45 and this would be below the reduced pipe part 25 which is below and outside of the casing. The asbestos washer 30 will be quite positive in preventing leaking at this point, as repeated tests have shown, but any 50 possible escape of gases at this point will only lead to the open ends of the cap 33, as before explained.

Assuming that the parts are assembled in the car floor and that it is desired to clean 55 or renovate the heater of all foreign matter that may have dropped through the cover onto the hot coils 10; it is only necessary to remove the screw 22 and take the cover 20 off to gain easy and ready access to the casing and its coils 10. If, however, it is more 60 advantageous to remove the coils also, the removal of the screws 23 as well will permit the bodily removal of the coils from the casing, the tubular parts 25 being readily 65 withdrawn from the asbestos lined flange

31, the tubes 32 remaining in position by being held upon the cap piece 33 which is riveted at 35 by its flanges 34 to the casing bottom 13. The parts may be readily reseated in position by replacing in reverse 70 order from their recited removal.

It will be obvious that various changes within the scope of the appended claims may be made, and it is especially to be noted that the tubing may be a single tube or divided into any number of tubes united at their ends adjacent the casing ends for fitting in the disclosed joint. The advantages will obviously be much the same from this 75 construction, whether one or more tubes are used. Further, while I have disclosed a dished ring for fitting between the shoulder of the tube portions leading from the heater and the casing bottom, in some instances other means such as an asbestos gasket may 80 well be substituted for the ring, and in other cases it is feasible to enlarge somewhat the said shoulder and rest the same directly on the casing floor, the latter being of sheet metal is yieldable to a greater or less degree 85 to permit the tightening of the bolts or screws 23 for drawing the tube parts 25 tightly against the gasket on the flanges 31, so that the desired end is attained in either 90 case—a tight joint, and the only possible 95 point of escape of gases from such joint being below the casing bottom.

What I desire to claim as new and useful is,—

1. In a motor exhaust heater, a casing 100 adapted to be seated in the floor of a vehicle and having inlet and outlet openings in its bottom, and a heating tube in said casing having integral tube parts extending down through and fitting snugly in said inlet and 105 outlet openings, in combination with connecting pipes fitting within said tube parts and having annular flanges spaced from their ends and receiving thereon the lower 110 ends of said tube parts, means depending from said casing bottom for contacting the said flanges to support said connecting pipes, whereby possible leakage at the resulting 115 joint between said pipes and tube will issue below the casing bottom.

2. In a motor exhaust heater, a casing 120 adapted to be seated in the floor of a vehicle and having inlet and outlet openings in its bottom, and a heating tube in said casing having integral tubular parts extending down through and fitting snugly in said inlet and outlet openings, in combination with tubular connections from the exhaust and escape pipes telescoping within said tubular 125 parts, external flanges about said connections limiting the position of the lower ends of said tubular parts, and asbestos gaskets above said flanges to form gas-proof connection between the flanges and the ends of said tubular parts resting thereon, said con- 130

nnection being below the casing bottom, whereby possible gas leakage at said flange connection will issue outside the casing.

3. In a motor exhaust heater, a casing adapted to be seated in the floor of a vehicle and having openings in its bottom, a heating tube in said casing having imperforate and integral tubular extensions adapted to pass through said openings, pipe means below said casing for connecting said extensions with exhaust and escape tubes, said pipe means and extensions having telescoping ends fitting snugly together to form a gas-tight joint, an angular supporting cap piece having open ends, side flanges for securing the same to the bottom of the casing, and a circular aperture in the main portion through which the connecting pipe means extends to form the said joint above the cap, the said pipe means having means spaced from its end for supporting the same from said cap, and the relation between the pipe means, cap and extensions being such that possible leak from said joint will issue outside said casing and through the open ends of the cap.

4. In a motor exhaust heater, a casing adapted to be seated in the floor of a vehicle and having openings in its bottom, a heating tube in said casing, downwardly extending tubular parts integral with said tube fitting snugly in and passing through said bottom openings, means for yieldingly forcing said tube and its downward extensions to their lowest limit, an angular cap plate having its ends open and its sides fixed to the bottom of the casing and having a circular aperture through its center portion slightly larger in diameter than the said extension, tubular connections fitting within said tubular parts and having annular flanges spaced from their ends and receiving thereon the lower ends of said tubular parts, the lower part of the said connections passing through said circular aperture with the said flange resting on the cap plate, whereby possible leakage at said flange connection will issue outside the casing and through said open ends of the cap.

5. In a motor exhaust heater, a casing adapted to be seated in the floor of a vehicle and having a plurality of openings in its bottom, a heating tube in said casing, a foraminous cover for the casing, downwardly extending tubular parts integral with said tube including reduced tube portions whereby a shoulder is formed thereabove, fitting snugly in and passing through said openings, dished metal rings encircling said reduced tube portions just beneath said shoulder and resting upon the casing bottom, attaching means connecting the casing bottom and tube for pressing the latter yieldingly downward against the force of said dished

rings, tubular connections fitting within said tubular parts and having annular flanges spaced from their ends and receiving thereon the lower ends of said tubular parts, means depending from said casing bottom on which the flanges rest for supporting said tubular connections, and means detachably connected with the bottom of the casing for holding the cover on the edges of the casing.

6. In a motor exhaust heater, a casing adapted to be seated in the floor of a vehicle and having openings in its bottom, a heating tube in said casing, downwardly directed tubular extensions integral with said tube fitting snugly in and passing through said bottom openings, tubular means below the casing bottom for connecting said tubular extensions with exhaust and escape pipes, said tubular connecting means and extensions having telescoping ends, one of said tubular elements having a flange spaced from its end to receive the corresponding end of the other tubular element thereon, there being an asbestos washer therebetween to form a joint below the casing to render the joint gas-tight, a cap piece angular in cross section and having side flanges adapted to be fixed to the lower side of the floor of the casing, the ends of the cap being open and its main part having a central aperture through which said tubular connecting means is threaded and supported upon the inner face of the cap, means connecting the casing and tube for pressing the latter tightly against the tubular connecting means, and yielding means within and supported by the casing for opposing said pressure.

7. In a motor exhaust heater, a casing adapted to be seated in the floor of a vehicle and having openings in its bottom, and an integral heating tube in said casing having reduced and integral tube parts extending down through and fitting snugly in said openings, in combination with connecting pipes leading from exhaust and escape pipes respectively, and fitting within the extended outward portions of the said reduced tube parts to form telescoping joints in which the lower ends of the said integral tube parts are below the lower surface of the casing bottom.

8. In a motor exhaust heater, a casing adapted to be seated in the floor of a vehicle and having openings in its bottom, and an integral heating tube in said casing having integral tube parts extending down through said bottom openings, in combination with connecting pipes leading from exhaust and escape pipes, respectively, and forming with said outward ends of the tube parts extended below said bottom opening, joints whose external point of connection is below the lower surface of the casing bottom.

9. A motor exhaust heater comprising a casing adapted to be seated in the floor of a

vehicle and having openings in its bottom, an integral and upwardly removable heating coil within said casing and having integral tubes leading therefrom and extending down through said openings and below said bottom, the joints for connecting said outward extended ends of said tubes with sources of heat being wholly below the casing bottom.

10. In a heater, a casing having a cleaning opening in its bottom, a closure for said opening, an upwardly removable unitary heating coil within the casing and over said opening and closure, tube parts integral with said coil extending downwardly through the casing bottom, connections with exhaust and escape pipes, respectively, for detachably uniting with said tube parts by joints wholly beneath the casing bottom, and means acces-

sible from above for fixing the coil and closure in position.

11. In a motor exhaust heater, a casing having a cleaning opening in its bottom, a closure for said opening seated on top of the bottom of the casing and removable upwardly therefrom, a unitary heater coil in the casing, a lug integral with the coil and depending therefrom and engaged with the top of the closure, downwardly-extending tube parts integral with said coil, connections beneath the said casing bottom for detachably uniting with said tube parts, and means accessible from above the casing for fixing the coil and closure in position.

In testimony whereof I hereunto affix my signature.

ASA E. LINENDOLI.
